US0D1025924S

(12) **United States Design Patent** (10) **Patent No.:** **US D1,025,924 S**
(45) **Date of Patent:** **** May 7, 2024**

(54) **CONNECTOR FOR A DATA PROCESSING EQUIPMENT**

- (71) Applicant: **Carre Technologies Inc.**, Montreal (CA)
- (72) Inventors: **Marc Castanet**, Hampstead (CA); **Sylvain Duchesne**, Bromont (CA); **Pierre-Alexandre Fournier**, Montreal (CA); **Robert Katz**, Montreal (CA); **Jean-François Roy**, Montreal (CA)
- (73) Assignee: **CARRE TECHNOLOGIES INC.**, Montreal (CA)

(**) Term: **15 Years**

(21) Appl. No.: **29/864,898**

(22) Filed: **Jun. 27, 2022**

(57) **CLAIM**

The ornamental design for a connector for a data processing equipment, as shown and described.

DESCRIPTION

FIG. 1 is a front elevation view of a connector for a data processing equipment;
FIG. 2 is a rear elevation view of the connector for a data processing equipment;
FIG. 3 is a top view of the connector for a data processing equipment;
FIG. 4 is a bottom view of the connector for a data processing equipment;
FIG. 5 is an enlarged left elevation view of the chip of the connector for a data processing equipment;
FIG. 6 is an enlarged right elevation view of the chip of the connector for a data processing equipment;
FIG. 7 is a front perspective view of the connector for a data processing equipment; and,
FIG. 8 is a rear perspective view of the connector for a data processing equipment.

The broken lines shown on the drawings depict portions of the connector for a data processing equipment that form no part of the claimed design.

1 Claim, 8 Drawing Sheets
